ABSTRACT OF THE DISCLOSURE

The compounds are of the class of N-substituted derivatives of norscopolamine and quaternary ammonium salts thereof, useful as central nervous system depressants, anticholinergics and spasmolytics.

This invention relates to novel N-substituted derivatives of norscopolamine and quaternary ammonium salts thereof, as well as to a process of preparing these compounds.

More particularly, the present invention relates to

(1) Novel racemic or optically active norscopolamine derivatives of the formula

wherein

R is straight or branched acyclic hydrocarbyl of 2 to 16 carbon atoms, monocyclic or bicyclic aryl, halo-substituted monocyclic or bicyclic aryl, alkoxy, alkoxycarbonyl, aliphatic or aromatic acyl of 1 to 10 carbon atoms, aliphatic or aromatic acyloxy of 1 to 10 carbon atoms, monoalkylamino of 1 to 20 carbon atoms, di-alkylamino of 2 to 20 carbon atoms, aralkylamino, hydroxy-substituted straight or branched alkyl of 1 to 16 carbon atoms, amino-substituted straight or branched alkyl of 1 to 16 carbon atoms, theophyllinyl-substituted straight or branched alkyl of 1 to 16 carbon atoms, cyano-substituted straight or branched alkyl of 1 to 16 carbon atoms, or cycloalkyl, and

R₁ is hydrogen or aliphatic, aromatic or araliphatic acyl of 2 to 16 carbon atoms,

(2) Non-toxic, pharmacologically acceptable acid addition salts thereof, and

(3) Quaternary salts thereof of the formula

wherein

R and R₁ have the same meanings as in Formula I, X is the anion of an acid, such as a hydrohalic acid or an aliphatic or aromatic sulfonic acid, and

R₂ is acyclic hydrocarbyl of 1 to 16 carbon atoms.

The norscopolamine derivatives of the Formula I above may be prepared by reacting norscopolamine or an O-acyl derivative thereof, that is, a compound of the formula

wherein R₁ has the same meanings as in Formula I, with a molar equivalent of a compound of the formula

2

wherein R has the same meanings as in Formula I, and X has the same meanings as in Formula Ia.

The reaction between compounds II and III is carried out under conditions which are customarily employed for reactions of this kind, that is, in the presence of an inert organic solvent and of an acid-acceptor, and at a temperature between the solidification point and boiling point of the reaction mixture. Examples of suitable inert organic solvents are ether, lower alkanols, benzene, toluene, carbon tetrachloride and preferably acetonitrile. If reactant III is itself a solvent for compound II, then a sufficient stoichiometric excess of compound III may simultaneously serve as the solvent medium for the reaction; in other words, under these conditions the reaction proceeds without the addition of a separate solvent. Examples of suitable acid-acceptors are inorganic bases and tertiary organic bases, such as sodium carbonate and trimethylamine. However, the use of a separate acid-acceptor is not obligatory; instead, a portion of the norscopolamine base, i.e. compound II, may simultaneously serve as the acid-acceptor. In those instances where the reaction mixture has a relatively high boiling point, i.e., in excess of 160° C., a reaction temperature of 120–160° C. is advantageously used.

In those instances where the above reaction yields a compound of the Formula I wherein R₁ is hydrogen, this reaction product may subsequently be transformed into the corresponding compound of the Formula I wherein R₁ is aliphatic, aromatic or araliphatic acyl by reacting said reaction product with a customary acylating agent. This acylation reaction may also be carried out in the presence of an inert organic solvent of the type referred to above. Examples of preferred acylating agents are acid halides and acid anhydrides which, upon hydrolysis, form the carboxylic acid corresponding to the desired meaning of R₁.

An optically active compound of the Formula I is generally prepared from the corresponding optically active starting compound of the Formula II; however, it may also be obtained by customary separation of the racemate into its optically active components with the aid of optically active auxiliary acids, such as dibenzoyl-D-tartaric acid or d-3-bromocamphor-8-sulfonic acid. For the preparation of a racemic compound of the Formula I a racemic starting compound of the Formula II is used.

The above described process yields a tertiary norscopolamine derivative of the Formula I, which may, if desired, be transformed pursuant to customary methods into a nontoxic, pharmacologically acceptable acid addition salt thereof; this transformation may, for example, be effected by acidifying a solution of the free tertiary base with the desired acid, or by double decomposition. Examples of acids which will form non-toxic, pharmacologically acceptable acid addition salts with a norscopolamine compound of the Formula I include, but are not limited to, hydrochloric acid, hydrobromic acid, sulfuric acid, methanesulfonic acid, lactic acid, tartaric acid, succinic acid, maleic acid, 8-chlorotheophylline and the like. For the double decomposition method it is advantageous to select as a reaction partner for the norscopolamine derivative addition salt a salt which forms with the anion to be replaced a difficultly soluble and therefore easily separable salt. For instance, if a hydrochloride addition salt is to be transformed into another acid addition salt, it is advantageous to use as a double decomposition reaction partner for the hydrochloride the silver salt of the anion to be introduced.

If desired, a tertiary norscopolamine derivative of the Formula I may be transformed into a corresponding

3

quaternary N-substituted norscopolammonium salt of the Formula Ia above by reacting the tertiary compound with an alkylating agent of the formula

wherein R_2 and X have the same meanings as in Formula Ia. The quaternization reaction is carried out under the same conditions as the reaction between compounds II and III, except that it is advantageous to use room temperature or an only slightly elevated reaction temperature, such as from 30 to 40°C. In order to obtain an optically active quaternary salt of the Formula Ia, the corresponding optically active tertiary compound of the Formula I must be used as the starting material; similarly, a racemic quaternary salt is prepared from the corresponding racemic tertiary compound.

In those instances where the quaternization reaction yields a compound of the Formula Ia wherein R_1 is hydrogen, this hydrogen atom may subsequently be replaced by an aliphatic, aromatic or araliphatic acyl radical of 2 to 16 carbon atoms in the same manner as described above in connection with the subsequent acylation of a tertiary compound of the Formula I wherein R_1 is hydrogen.

R_1 is hydrogen. The anion X^- in a quaternary compound of the Formula Ia obtained by any of the above methods may, if desired, be exchanged for another anion by customary procedures, such as by double decomposition; the double decomposition reaction is carried out in the same manner and under the same conditions as the double decomposition reaction described above in connection with the conversion of an acid addition salt of a tertiary compound I into another acid addition salt.

The following examples further illustrate the present invention and will enable others skilled in the art to understand the invention more completely. It should be understood, however, that the invention is not limited to the particular illustrative examples given below:

EXAMPLE 1

Preparation of (–)-N-ethyl-norscopolamine and its hydrochloride

14.5 gm. (0.05 mol) of (—)-norscopolamine and 5.4 gm. (0.05 mol) of ethyl bromide were dissolved in 30 cc. of acetonitrile, 5.3 gm. (0.05 mol) of anhydrous sodium carbonate were suspended in the solution, and the suspension was heated at the boiling point for ten hours. After a boiling time of 2.5 and 5 hours, respectively, the supply of ethyl bromide and sodium carbonate in the reaction mixture was replenished by adding each time 5.4 gm. (0.05 mol) of ethyl bromide and 5.3 gm. (0.05 mol) of anhydrous sodium carbonate. At the end of ten hours of boiling, the inorganic sodium salts which had separated out were separated by vacuum filtration, the filter cake was washed with acetonitrile, and the acetonitrile was distilled out of the filtrate. The distillation residue was dissolved in ether, the solution was extracted with a small amount of water and then dried, and the ether was distilled off, yielding raw (—)-N-ethyl-norscopolamine. The calculated amount of hydrogen chloride was added to the raw base, whereby the raw hydrochloride thereof was obtained, which was recrystallized from acetonitrile. 15.1 gm. (85.1% of theory) of white crystalline (—)-N-ethyl-norscopolamine hydrochloride, M.P. 188–190° C., specific rotation

(c. = 2.0), of the formula

were obtained.

4

EXAMPLE 2

Using a procedure analogous to that described in Example 1, (-)-N-n-propyl-norscopolamine hydrochloride, white crystals (from acetonitrile), M.P. 177-178° C., specific rotation $[\alpha]_{20}^D = -30^\circ$ C. (c. = 2.0), was prepared from scopolamine and propyl bromide. The total heating time was 20 hours, and the propyl bromide and sodium carbonate were replenished after five and eight hours of heating. The yield was 15.8 gm. (85.8% of theory).

EXAMPLE 3

Using a procedure analogous to that described in Example 1, (—)-N-n-butyl-norscopolamine hydrochloride, white crystals (from acetone), M.P. 146–148° C., specific rotation $[\alpha]_{20}^D = 28.5^\circ$ (c. = 2.0), was prepared from n-butyl bromide and scopolamine. The total heating time was 20 hours, and the butyl bromide and sodium carbonate were replenished after five and eight hours of heating. The yield was 57.5% of theory.

EXAMPLE 4

Using a procedure analogous to that described in Example 1, (—)-N-n-amyl-norscopolamine hydrochloride, white crystals (from acetonitrile), M.P. 160–162° C., specific rotation $[\alpha]_D^{25} = -29.5^\circ$ (c=2.0), was prepared from n-amyl bromide and norscopolamine. The total heating time was 20 hours, and the amyl bromide and sodium carbonate were replenished after five and eight hours of heating. The yield was 16.7 gm. (84.3% of theory).

EXAMPLE 5

Preparation of (—)-N-n-hexyl-norscopolamine hydrobromide

35 14.5 gm. (0.05 mol) of (—)-norscopolamine and 8.3 gm. (0.05 mol) of n-hexyl bromide were dissolved in 25 cc. of acetonitrile, and the solution was heated to its boiling point. After about 1.5 hours of boiling a crystalline precipitate of (—)-norscopolamine hydrobromide separated out, which went into solution again in the course of 50 hours of boiling. Thereafter, the acetonitrile was distilled off, and the residue was dissolved in boiling acetone. Upon cooling the solution, a crystalline precipitate formed which was collected and recrystallized from acetone. 12.0 gm. (52.9% of theory) of white crystalline (—)-N-n-hexyl-norscopolamine hydrobromide, M.P. 150–152° C., specific rotation $[\alpha]_{20}^D = -25^\circ$ ($c = 2.0$), were obtained.

EXAMPLE 6

Preparation of (-)-N-n-heptyl-norscopolamine and its hydrochloride

55 14.5 gm. (0.05 mol) of (–)-norscopolamine were dis-
 solved in 30 gm. of n-heptyl bromide, 26.5 gm. (0.25
 mol) of anhydrous sodium carbonate were suspended in
 the solution, and the suspension was heated for five hours
 at 140° C. Thereafter, the inorganic sodium salts which
 had separated out were collected by vacuum filtration, the
 60 filter cake was washed, and the excess unreacted n-heptyl
 bromide was distilled out of the filtrate in vacuo, leaving
 as a residue raw (–)-N-n-heptyl-norscopolamine. The
 residue was admixed with the calculated amount of hy-
 65 drogen chloride, and the product formed thereby was re-
 crystallized from a mixture of methanol and ether. 12.5
 gm. (58.9% of theory) of white crystalline (–)-N-n-
 heptyl-norscopolamine hydrochloride, M.P. 150–157° C.,
 were obtained.

EXAMPLE 7

Using a procedure analogous to that described in Example 6, $(-)$ -N-n-octyl-norscopolamine hydrochloride, white crystals (from acetone/ether), M.P. 153-154° C., was prepared from $(-)$ -norscopolamine and n-octyl bromide. The yield was 15.5 gm. (70.7% of theory).

5
EXAMPLE 8

Using a procedure analogous to that described in Example 6, (—)-N-isonyl-norscopolamine hydrochloride, white crystals (from methanol/ether), M.P. 191–194° C. (decomposition), was prepared from (—)-norscopolamine and isonyl bromide. The yield was 87.3% of theory.

EXAMPLE 9

Using a procedure analogous to that described in Example 6, (—)-N-n-decyl-norscopolamine hydrochloride, white crystals (from ethyl acetate), M.P. 149–150° C., was prepared from (—)-norscopolamine and n-decyl bromide. The yield was 15 gm. (64.3% of theory).

EXAMPLE 10

Using a procedure analogous to that described in Example 6, (—)-N-n-undecyl-norscopolamine hydrochloride, white crystals (from acetone/ether), M.P. 128° C., was prepared from (—)-norscopolamine and n-undecyl bromide. The yield was 14 gm. (58.3% of theory).

EXAMPLE 11

Preparation of (—)-N-ethyl-norscopolamine methobromide

7.0 gm. (0.022 mol) of (—)-N-ethyl-norscopolamine were dissolved in acetonitrile, 10.4 gm. (0.11 mol) of methyl bromide were added to the solution, and the mixture was allowed to stand at room temperature. The crystalline precipitate formed thereby was collected and recrystallized from acetonitrile. 8.9 gm. (97.8% of theory) of white crystalline (—)-N-ethyl-norscopolamine methobromide, M.P. 203–204° C. (decomposition), specific rotation $[\alpha]_{21}^D = -25^\circ$ (c.=2.0), of the formula

were obtained.

EXAMPLE 12

Using a procedure analogous to that described in Example 11, (—)-N-n-butyl-norscopolamine methobromide, M.P. 188–189° C. (decomposition), specific rotation $[\alpha]_{25}^D = -26.5^\circ$ (c.=2.0), was prepared from (—)-N-n-butyl-norscopolamine and methyl bromide. The yield was 4.5 gm. (95.7% of theory).

EXAMPLE 13

Using a procedure analogous to that described in Example 11, (—)-N-n-hexyl-norscopolamine methobromide, white crystals (from methanol/ether), M.P. 169–170° C. (decomp.), specific rotation $[\alpha]_{20}^D = -25.7^\circ$ (c.=1.986), was prepared from (1)-N-n-hexyl-norscopolamine and methyl bromide. The yield was 16.7 gm. (83.1% of theory).

EXAMPLE 14

Using a procedure analogous to that described in Example 11, (—)-N-n-heptyl-norscopolamine methobromide, white crystals (from methanol/ether), M.P. 179–180° C. (decomposition), was prepared from n-heptyl-norscopolamine and methyl bromide. The yield was 7.9 gm. (87.7% of theory).

EXAMPLE 15

Using a procedure analogous to that described in Example 11, (—)-N-n-octyl-norscopolamine methobromide, white crystals (from methanol/ether), M.P. 179–180° C. (decomposition), specific rotation $[\alpha]_{20}^D = -26.6^\circ$ (c.=0.977), was prepared from (—)-N-n-octyl-norscopolamine and methyl bromide. The yield was 11.5 gm. (94.9% of theory).

EXAMPLE 16

Using a procedure analogous to that described in

6

Example 11, (—)-N-isonyl-norscopolamine methobromide, white crystals (from methanol/ether), M.P. 193–194° C. (decomposition), specific rotation

$$[\alpha]_{20}^D = -27.5^\circ \text{ C.}$$

5 C. (c.=1.0), was prepared from (—)-N-isonyl-norscopolamine and methyl bromide. The yield was 9.0 gm. (81.9% of theory).

EXAMPLE 17

10 Using a procedure analogous to that described in Example 11, (—)-N-decyl-norscopolamide methobromide, white crystals (from methanol/ether), M.P. 168–169° C. (decomposition), was prepared from (—)-N-n-decyl-norscopolamine and methyl bromide. The yield was 10.0 gm. (91.7% of theory).

EXAMPLE 18

20 Using a procedure analogous to that described in Example 11, (—)-N-n-undecyl-norscopolamine methobromide, white crystals (from methanol/ether), M.P. 176–177° C. (decomposition), was prepared from (—)-N-n-undecyl-norscopolamine and methyl bromide. The yield was 6.8 gm. (93.4% of theory).

EXAMPLE 19

25 Using a procedure analogous to that described in Example 11, (—)-N-n-dodecyl-norscopolamine methobromide, white crystals (from methanol/ether), M.P. 179–180° C. (decomposition), was prepared from (—)-N-n-dodecyl-norscopolamine and methyl bromide. The yield was 6.3 gm. (84.1% of theory).

EXAMPLE 20

30 35 Using a procedure analogous to that described in Example 1, (±)-N-isopropyl-norscopolamine hydrochloride, white crystals (from methanol/ether), M.P. 213–214° C. (decomp.), specific rotation $[\alpha]_{20}^D = \pm 0$ (c.=2.0), was prepared from (±)-norscopolamine and isopropyl bromide. The total reaction time was nine days, and the supply of isopropyl bromide and sodium carbonate was replenished once a day for seven days.

EXAMPLE 21

40 45 Using a procedure analogous to that described in Example 1, (—)-N-isopropyl-norscopolamine hydrochloride, white crystals (from ethanol), M.P. 214–216° C. (decomp.), specific rotation $[\alpha]_{20}^D = -27.3^\circ$ (c.=2.0), was prepared from (—)-norscopolamine and isopropyl bromide. The total reaction time was 60 hours, and the supply of isopropyl bromide and sodium carbonate was replenished after 5, 8 and 17 hours. The yield was 4.5 gm. (21.1% of theory).

EXAMPLE 22

50 55 Using a procedure analogous to that described in Example 6, (±)-N-n-butyl-norscopolamine hydrochloride, white crystals (from acetone), M.P. 133–134° C., specific rotation $[\alpha]_{20}^D = \pm 0^\circ$ (c.=2.0), was prepared from (—)-norscopolamine, n-butyl bromide and sodium carbonate. The total reaction time was 24 hours at 100° C.

EXAMPLE 23

60 65 Using a procedure analogous to that described in Example 4, (—)-N-isoamyl-norscopolamine hydrochloride, white crystals (from acetonitrile), M.P. 186–188° C., specific rotation $[\alpha]_{20}^D = -28.0^\circ$ (c.=2.0), was prepared from (—)-norscopolamine and isoamyl bromide. The total reaction time was 22.5 hours. The yield was 17.2 gm. (86.9% of theory).

EXAMPLE 24

70 Using a procedure analogous to that described in Example 6, (±)-N-n-hexyl-norscopolamine hydrochloride, white crystals (from acetone), M.P. 144–153° C., specific rotation $[\alpha]_{20}^D = \pm 0^\circ$, was prepared from (±)-

was prepared from (—)-norscopolamine, bromoacetone and sodium carbonate. The total reaction time was ten hours, and 0.005 mol of bromoacetone was added after 4.5 hours. The yield was 5.9 gm. (30.9% of theory).

EXAMPLE 38

Using a procedure analogous to that described in Example 1, (—)-N-phenoxyl-norscopolamine hydrochloride, white crystals (from methanol/ether), M.P. 176–179° C. (decomp.), specific rotation $[\alpha]_{20}^D = -33.0^\circ$ (c.=2.0), was prepared from 13.9 gm. (0.048 mol) of (—)-norscopolamine, 9.6 gm. (0.048 mol) of bromoacetophenone and 5.1 gm. (0.048 mol) of sodium carbonate. The total reaction time was 2.5 hours, and the supply of reactant and sodium carbonate was not replenished. The yield was 8.4 gm. (39.4% of theory).

EXAMPLE 39

Using a procedure analogous to that described in Example 1, (—)-N-hydroxyethyl-norscopolamine hydrochloride, white crystals (from methanol/ether), M.P. 182–183° C. (decomp.), specific rotation $[\alpha]_{20}^D = -21.5^\circ$ (c.=2.0), was prepared from (—)-norscopolamine, bromoethanol and sodium carbonate. The total reaction time was 30 hours, and 0.025 mol of bromoethanol and 0.025 mol of sodium carbonate were added after 5, 16 and 19 hours. The yield was 16.2 gm. (87.6% of theory).

EXAMPLE 40

Using a procedure analogous to that described in Example 1, (—)-N-β-cyanoethyl-norscopolamine, white crystals (from water), M.P. 106° C., was prepared from (—)-norscopolamine, β-bromo-propionitrile and sodium carbonate. The total reaction time was 90 hours, and 0.025 mol of β-bromopropionitrile and 0.025 mol of sodium carbonate were added after 7, 14, 28, 54 and 61 hours. The yield was 10.1 gm. (59.0% of theory).

EXAMPLE 41

Using a procedure analogous to that described in Example 11, (—)-N-n-propyl-norscopolamine methobromide, white crystals (from acetonitrile), M.P. 181–182° C. (decomp.), specific rotation $[\alpha]_{20}^D = -28.3^\circ$ (c.=2.0), was prepared from (—)-N-n-propyl-norscopolamine and methyl bromide. The yield was 88.7% of theory.

EXAMPLE 42

Using a procedure analogous to that described in Example 11, (—)-N-isopropyl-norscopolamine methobromide, white crystals (from methanol/ether), M.P. 216° C. (decomp.), specific rotation $[\alpha]_{20}^D = -13.8^\circ$ (c.=2.0), was prepared from (—)-N-isopropyl-norscopolamine and methyl bromide. The yield was 44.3% of theory.

EXAMPLE 43

Using a procedure analogous to that described in Example 11, (±)-N-n-butyl-norscopolamine methobromide, white crystals (from acetonitrile/ether), M.P. 163–165° C. (decomp.), specific rotation $[\alpha]_{20}^D = \pm 0^\circ$ (c.=2.0), was prepared from (±)-N-n-butyl-norscopolamine and methyl bromide. The yield was 66.3% of theory.

EXAMPLE 44

Using a procedure analogous to that described in Example 11, (—)-N-allyl-norscopolamine methobromide, white crystals (from acetonitrile), M.P. 157–158° C. (decomp.), specific rotation $[\alpha]_{20}^D = -28.5^\circ$ (c.=2.0), was prepared from (—)-N-n-amyl-norscopolamine and methyl bromide. The yield was 84.3% of theory.

EXAMPLE 45

Using a procedure analogous to that described in Example 11, (—)-N-isoamyl-norscopolamine methobro-

mide, white crystals (from acetonitrile), M.P. 178–178.5° C. (decomp.), specific rotation $[\alpha]_{20}^D = -26.2^\circ$ (c.=2.0), was prepared from (—)-N-isoamyl-norscopolamine and methyl bromide. The yield was 78.9% of theory.

10

EXAMPLE 46

Using a procedure analogous to that described in Example 11, (—)-N-n-nonyl-norscopolamine methobromide, white crystals (from methanol/ether), M.P. 170–171° C. (decomp.), was prepared from (—)-N-n-nonyl-norscopolamine and methyl bromide. The yield was 85.0% of theory.

EXAMPLE 47

Using a procedure analogous to that described in Example 11, (—)-N-n-hexadecyl-norscopolamine methobromide, white crystals (from acetone), M.P. 174–175° C. (decomp.), was prepared from (—)-N-n-hexadecyl-norscopolamine and methyl bromide. The yield was 75.8% of theory.

EXAMPLE 48

Using a procedure analogous to that described in Example 11, (—)-N-allyl-norscopolamine methobromide, white crystals (from acetonitrile/ether), M.P. 182.5–183° C. (decomp.), specific rotation $[\alpha]_{20}^D = -27.0^\circ$ (c.=2.0), was prepared from (—)-N-allyl-norscopolamine and methyl bromide. The total reaction time was five days. The yield was 77.6% of theory.

EXAMPLE 49

Using a procedure analogous to that described in Example 11, (—)-N-benzyl-norscopolamine methobromide, white crystals (from ethanol/ether), M.P. 180–181° C. (decomp.), was prepared from (—)-N-benzyl-norscopolamine and methyl bromide. The total reaction time was ten days. The yield was 8.0% of theory.

EXAMPLE 50

Using a procedure analogous to that described in Example 11, (—)-N-4-diphenylmethyl-norscopolamine methobromide, white crystals (from methanol/ether), M.P. 191–192° C. (decomp.), was prepared from (—)-N-4-diphenylmethyl-norscopolamine and methylbromide. The total reaction time was one month. The yield was 18.2% of theory.

EXAMPLE 51

Using a procedure analogous to that described in Example 11, (—)-N-ethoxycarbonylmethyl-norscopolamine methobromide, white crystals (from ethanol/ether), M.P. 170° C. (decomp.), specific rotation $[\alpha]_{20}^D = -27.5^\circ$ (c.=2.0), was prepared from (—)-N-ethoxycarbonylmethyl-norscopolamine and methyl bromide. The total reaction time was ten days. The yield was 53.1% of theory.

EXAMPLE 52

Using a procedure analogous to that described in Example 11, (—)-N-β-hydroxyethyl-norscopolamine methobromide, white crystals (from ethanol), M.P. 211° C. (decomp.), specific rotation $[\alpha]_{20}^D = -20.5^\circ$ (c.=2.0), was prepared from (—)-N-β-hydroxyethyl-norscopolamine and methyl bromide. The total reaction time was five days. The yield was 64.8% of theory.

EXAMPLE 53

Using a procedure analogous to that described in Example 11, (—)-N-ethyl-norscopolamine bromoallylate, white crystals (from methanol/ether), M.P. 175–176° C. (decomp.), specific rotation $[\alpha]_{20}^D = -20^\circ$ (c.=2.0) of the formula

75 was prepared from 8.6 gm. (0.027 mol) of (—)-N-ethyl-

norscopolamine and 6.6 gm. (0.054 mol) of allyl bromide in 20 cc. of acetonitrile. The total reaction time was eight days. The yield was 8.2 gm. (69.2% of theory).

EXAMPLE 54

Using a procedure analogous to that described in Example 53, (—)-N-n-propyl-norscopolamine bromoallylate, white crystals (from methanol/ether), M.P. 154–155° C. (decomp.), specific rotation $[\alpha]_{20}^D = -23.8^\circ$ (c.=2.0), was prepared from (—)-n-propyl-norscopolamine and allyl bromide. The yield was 70.3% of theory.

EXAMPLE 55

Preparation of (—)-N-n-heptyl-norscopolamine methomethanesulfonate

13.5 gm. (0.035 mol) of (—)-N-n-heptyl-norscopolamine were dissolved in 20 cc. of acetonitrile, 4.4 gm. (0.04 mol) of methyl methanesulfonate were added to the solution, and the mixture was allowed to stand for six days at 60° C. The precipitate formed thereby was collected and recrystallized from a mixture of acetone and ether. 10.2 gm. (59.0% of theory) of white crystalline (—)-N-n-heptyl-norscopolamine methomethanesulfonate, M.P. 135° C., specific rotation $[\alpha]_{20}^D = -20^\circ$ C. (c.=2.0), were obtained.

EXAMPLE 56

Using a procedure analogous to that described in Example 55, (—)-N-n-octyl-norscopolamine methomethanesulfonate, white crystals (from acetone/ether), M.P. 166.5–167.5° C., specific rotation $[\alpha]_{20}^D = -22.5^\circ$ (c.=2.0), was prepared from (—)-N-n-octyl-norscopolamine and methyl methanesulfonate. The yield was 44.6% of theory.

EXAMPLE 57

Using a procedure analogous to that described in Example 55, (—)-N-n-nonyl-norscopolamine methomethanesulfonate, white crystals (from acetone/ether), M.P. 131–132° C., specific rotation $[\alpha]_{20}^D = -23.75^\circ$ (c.=2.0), was prepared from (—)-N-n-nonyl-norscopolamine and methyl methanesulfonate. The total reaction time was four weeks. The yield was 59.2% of theory.

EXAMPLE 58

Using a procedure analogous to that described in Example 55, (—)-N-n-decyl-norscopolamine methomethanesulfonate, white crystals (from acetone), M.P. 119–120° C., specific rotation $[\alpha]_{20}^D = -25.0^\circ$ (c.=2.0), was prepared from (—)-N-n-decyl-norscopolamine and methyl methanesulfonate. The yield was 70.8% of theory.

EXAMPLE 59

Using a procedure analogous to that described in Example 55, (—)-N-n-dodecyl-norscopolamine methomethanesulfonate, white crystals (from acetone), M.P. 110–111° C., specific rotation $[\alpha]_{20}^D = -22.5^\circ$ (c.=2.0), was prepared from (—)-N-n-dodecyl-norscopolamine and methyl methanesulfonate. The yield was 57.7% of theory.

EXAMPLE 60

Using a procedure analogous to that described in Example 55, (—)-N-n-hexadecyl-norscopolamine methomethanesulfonate, white crystals (from acetone), M.P. 98–99° C., specific rotation $[\alpha]_{20}^D = -20.5^\circ$ (c.=2.0), was prepared from (—)-N-n-hexadecyl-norscopolamine and methyl methanesulfonate. The yield was 23.5% of theory.

The compounds according to the present invention, that is, those embraced by Formula I, their nontoxic, pharmacologically acceptable acid addition salts and their quaternary salts of the Formula Ia, have useful pharmacodynamic properties. More particularly, they exhibit central nervous system depressing and anticholinergic (spasmolytic) properties in warm-blooded animals.

In the quaternary salts of the Formula Ia the spasmolytic activity predominates; especially active in this respect are the levorotatory (—) quaternary salts of the Formula Ia wherein R is an acyclic, saturated or unsaturated hydrocarbon, such as (—)-N-ethyl-norscopolamine methobromide or (—)-N-allyl-norscopolamine methobromide.

For pharmaceutical purposes the compounds of the instant invention are administered to warm-blooded animals perorally or parenterally as active ingredients in customary dosage unit compositions, that is, compositions in dosage unit form consisting essentially of an inert pharmaceutical carrier and one dosage unit of the active ingredient, such as tablets, coated pills, solutions, suspensions, emulsions, wettable powders, syrups, capsules, wafers suppositories and the like. One dosage unit of the compound according to the present invention is from 0.08 to 5.0 mgm./kg. body weight, preferably from 0.16 to 3.3 mgm./kg. body weight. If desired, a dosage unit composition according to the present invention may also comprise one or more other active ingredients, such as analgesics, antiphlogistics, psychotherapeutics, sedatives and tranquilizers.

The following examples illustrate a few dosage unit compositions comprising a compound of the invention as an active ingredient. The parts are parts by weight unless otherwise specified.

EXAMPLE 61

Hypodermic solution

The solution is compounded from the following ingredients:

	Parts
(—)-N-ethyl-norscopolamine methobromide	10.0
Dextrose	47.0
Tartaric acid	0.012
Double-distilled water, q.s. ad. 2000.0	parts by vol.

Compounding procedure.—The individual ingredients are dissolved in the required amount of freshly double-distilled water, the solution is filtered until free from suspended matter, and the filtrate is filled under aseptic conditions into 2 cc.-ampules which are subsequently sterilized for 20 minutes at 120° C. and sealed. Each ampule contains 10 mgm. of the quaternary norscopolamine compound.

EXAMPLE 62

Suppositories

The suppository composition is compounded from the following ingredients:

	Parts
(—)-N-n-propyl-norscopolamine methomethanesulfonate	10.0
Lactose	100.0
Cocoa butter	1630.0
Total	1740.0

Compounding procedure.—The norscopolamine compound is admixed with the lactose, and the mixture is homogeneously distributed in the molten cocoa butter. The composition is then poured into cooled suppository molds, each holding 1740 mgm. of the composition. Each finished suppository contains 10 mgm. of the active ingredient.

EXAMPLE 63

Coated pills

The pill core composition is compounded from the following ingredients:

	Parts
(—)-N-ethyl-norscopolamine hydrochloride	10.0
Dicalcium phosphate	20.0
Lactose	13.9
Corn starch	30.0

Colloidal silicic acid	3.0
Tartaric acid	0.5
Soluble starch	2.0
Stearic acid	0.5
Food coloring	0.1
Total	80.0

Compounding procedure.—The norscopolamine compound is intimately admixed with about one-half the indicated amount of each of the other ingredients except the soluble starch, and the mixture is moistened with an aqueous solution of the soluble starch. The moist mass is granulated by forcing it through a fine-mesh screen, the granulate is dried and then admixed with the remaining half of the ingredients, and the composition is pressed into 80 mgm.-pill cores, which are subsequently coated with a thin shell of a customary pill-coating composition consisting essentially of titanium dioxide, sugar, gum arabic, polyvinylpyrrolidone and talcum. Each finished coated pill contain 10 mgm. of the norscopolamine compound.

EXAMPLE 64

Enteric-coated pills

The pill core composition is compounded from the following ingredients:

Parts	
(-)-N-ethyl-norscopolamine bromoallylate	100.0
Corn starch	168.0
Lactose, pulverized	76.0
Soluble starch	7.5
Colloidal silicic acid	6.0
Magnesium stearate	2.0
Polyvinylpyrrolidone	5.0
Total	365.0

Compounding procedure.—The pill cores are prepared in a manner analogous to that described in Example 63, except that the composition is pressed into 365 mgm.-pill cores. The latter are then coated with a thin enteric shell with the aid of a solution of 43.0 parts of cellulose acetate phthalate in an organic solvent. The enteric-coated pills are thereafter provided with an additional coating as in Example 63. Each coated pill contains 100 mgm. of the norscopolamine compound.

EXAMPLE 65

Suppositories with additional active ingredient

The suppository composition is compounded from the following ingredients:

Parts	
(1)-N-n-propyl-norscopolamine maleate	30.0
Metamizol	10.0
Lechithin	2.0
Cocoa butter	179.0
Total	221.0

The compounding procedure is the same as in Example 62, except that each suppository mold holds 221 mgm. of the composition. Each suppository contains 30 mgm. of the norscopolamine compound and 10 mgm. of metamizol an antipyretic and analgesic.

EXAMPLE 66

Drop solution for oral administration

The solution is compounded from the following ingredients:

Parts	
(1)-N-n-butyl - norscopolamine methomethanesulfonate	3.0
p-Hydroxybenzoic acid methyl ester	0.07
p-Hydroxybenzoic acid propyl ester	0.03
Ethanol, 2000.0 parts by vol.	
Demineralized water, q.s. ad. 100,000.0 parts by vol.	

Compounding procedure.—The quaternary norscopolamine compound is dissolved in the demineralized water, and the solution is admixed with a solution of the p-hydroxybenzoic acid esters in the ethanol. 1 cc. of the finished solution (20 drops) contains 0.03 mgm. of the norscopolamine compound.

EXAMPLE 67

Coated pills with additional active ingredient

The pill core composition is compounded from the following ingredients:

Parts	
(±)-N-n-heptyl-norscopolamine bromoallylate	10.0
3 - hydroxy-5-phenyl-7-chloro-1,3-dihydro-2H-1,4-benzodiazepin-2-one	10.0
Dicalcium phosphate	48.0
Lactose	25.0
Corn starch	60.0
Colloidal silicic acid	3.0
Soluble starch	3.0
Stearic acid	1.0
Total	160.0

The compounding procedure is analogous to that of Example 63, except that 160 mgm.-pill cores are formed. Each coated pill contains 10 mgm. of the quaternary norscopolamine compound and 10 mgm. of the benzodiazepinone compound.

Although the above dosage unit composition examples illustrate only seven specific compounds of the instant generic invention as active ingredients, it should be understood that any other compounds embraced by Formula I or a nontoxic, pharmacologically acceptable acid addition salt thereof, or any other quaternary salt embraced by Formula Ia may be substituted for the particular norscopolamine compound illustrated in Examples 61 through 67. Moreover, the amount of active ingredient in these examples may be varied to achieve the dosage unit range set forth above, and the amounts and nature of the inert pharmaceutical carrier ingredients may be varied to meet particular requirements.

While the present invention has been illustrated with the aid of certain specific embodiments thereof, it will be readily apparent to others skilled in the art that the invention is not limited to these particular embodiments and that various changes and modifications may be made without departing from the spirit of the invention or the scope of the appended claims.

We claim:

1. The levorotatory compound of the formula
$$\left[\begin{array}{c} \text{CH}-\text{CH} \quad \text{CH}_2 \quad \text{O} \\ | \quad \quad \quad | \quad \quad \quad || \\ \text{O} \quad \text{N}-\text{CH}_2-\text{CH}=\text{CH}_2 \quad \text{CH}-\text{O}-\text{C}-\text{CH}-\text{C}_6\text{H}_5 \\ | \quad \quad \quad | \\ \text{CH}-\text{CH} \quad \text{CH}_3 \quad \text{CH}_2\text{OH} \end{array} \right] \cdot \text{HCl}$$
2. The levorotatory compound of the formula
$$\left[\begin{array}{c} \text{CH}-\text{CH} \quad \text{CH}_2 \quad \text{O} \\ | \quad \quad \quad | \quad \quad \quad || \\ \text{N}_3\text{C}-\text{N}^+-\text{CH}_2-\text{CH}=\text{CH}_2 \quad \text{CH}-\text{O}-\text{C}-\text{CH}-\text{C}_6\text{H}_5 \\ | \quad \quad \quad | \\ \text{CH}-\text{CH} \quad \text{CH}_2 \quad \text{CH}_2\text{OH} \end{array} \right] \cdot \text{Br}^-$$
3. The levorotatory compound of the formula
$$\left[\begin{array}{c} \text{CH} \quad \text{OH} \quad \text{CH}_2 \quad \text{O} \\ | \quad \quad \quad | \quad \quad \quad || \\ \text{H}_2\text{C}=\text{CH}-\text{CH}_2-\text{N}^+-\text{n}-\text{C}_6\text{H}_5 \quad \text{CH}-\text{O}-\text{C}-\text{CH}-\text{C}_6\text{H}_5 \\ | \quad \quad \quad | \\ \text{CH} \quad \text{CH}_2 \quad \text{CH}_2\text{OH} \end{array} \right] \cdot \text{Br}^-$$

UNITED STATES PATENT OFFICE
CERTIFICATE OF CORRECTIONPatent No. 3,472,861Dated October 14, 1969Inventor(s) KARL ZEILE, ROLF BANHOLZER, GERHARD WALTER,
WERNER SCHULZ and HELMUT WICK

It is certified that error appears in the above-identified patent and that said Letters Patent are hereby corrected as shown below:

Column 9, line 43 - "20D" should read --20--. ^D
Column 11, line 25 - "-20°" should read -- -25° --.
Column 13, line 54 - correct the spelling of "Lecithin".
Column 14, line 58 - in the formula of Claim 2
"N₃C" should read --H₃C--.
